UNITED STATES PATENT OFFICE.

OSCAR T. EARLE, OF MILFORD, CONNECTICUT.

HOSE-BAND.

SPECIFICATION forming part of Letters Patent No. 224,586, dated February 17, 1880.

Application filed December 8, 1879.

To all whom it may concern:

Be it known that I, OSCAR T. EARLE, of Milford, in the county of New Haven, and in the State of Connecticut, have invented an Improvement in Hose-Bands, of which the following is a specification.

This invention relates to an improvement in hose-bands and a method of applying the same, and is substantially developed from the improved hose-band invented by me and patented, No. 172,982.

In the drawings, Figure 1 represents a hose-coupling with a hose upon it and the band in sight in exterior view. Fig. 2 is a cross-section at the line $x x$ of Fig. 1. Fig. 3 is a longitudinal section at the line $x x$ of Fig. 1. Fig. 4 is a similar cross-section of a slightly-modified form of the contrivance. Fig. 5 is a similar longitudinal section of such modified form; and Figs. 6 and 7 show means for compressing, fitting, and applying the hose-bands to the hose, &c.

Like letters indicate like parts in all the figures.

25 A is the coupling, formed in the usual manner, of metal, and properly prepared on its exterior to receive the flexible hose. B is the flexible hose, which is adapted to be slipped over the coupling, also in the usual manner.

30 In order to confine the coupling and hose together, it has been usual heretofore to wrap them with wire, or, in the case of large hose, to put around the hose a hinged collar or a pair of half-collars provided with ears, through 35 which is inserted a bolt, by which the sides of the collar are drawn together and compress the flexible hose upon the coupling.

The improvement which I originally made in hose-bands was well adapted to small hose, 40 and was also serviceable for the larger kind of hose; but the present improvement is one that is somewhat more economical of material, inasmuch as a heavy clasp may be combined with a light strap, and is also more easily 45 made and is quite as easily applied.

C is the burr, and D is the strap. A hook is formed on one end of the strap D, and is hooked into one side of the burr C, its free end being so adjusted as to lie next the hose 50 B at a point about the middle of the neck of the coupling, which should be made in the

usual way, either corrugated along the whole length, as is usual in small couplings, or beaded at its inner end. The strap D is then passed through the other side of the burr C 55 and tightly drawn up, so as to embed itself in the hose and compress the hose firmly upon the neck of the coupling. As I have said, it is best to make the burr of thicker metal than the strap.

60 I have described this contrivance as employing a burr and a strap of sheet metal; but it is obvious round wires may be used in lieu of flat metal, and Figs. 4 and 5 represent (D') the use of round wires, either singly or in gangs, 65 in connection with this burr I have described. The burr is a piece of metal with a suitably-shaped hole pierced in it to receive the band. If the band is of round wires, this hole may be formed either round or oval, so as to give a 70 considerably transverse bearing to the wires, or it may be formed oblong and a gang of wires used.

75 Although the burr and band of this apparatus bear a certain resemblance to a cotton-bale tie, yet when the nature of the operation of this apparatus is compared with the nature of the operation of the cotton-bale tie it will be seen that there is a fundamental difference 80 between them.

A cotton-bale or any other bale of goods is compressible throughout its bulk, and in the application of the ties they are put onto the bale somewhat slack, when that is compressed by machinery beyond the bulk which it assumes 85 when banded and released from the press, so that the tightening of the bands is due to the elasticity of the compressed material.

In the case of a hose we have a non-compressible core with a compressible exterior, 90 which we wish to bind to the non-compressible core, in order that it may so closely cling to the core as not to slide upon it longitudinally. In order to do this it is necessary that the strain should be applied over the place of the 95 band, and that the band itself should be positively forced into its compressing position. In order to do this it is desirable to have a tool composed of a flexible strap or chain adapted to surround the coupling over the 100 place of the band and to be drawn together by a screw or other power, so as to shorten the

band by actual pressure upon its exterior surface and embed it in the compressible material of the hose itself, thereby bringing it into close contact with the neck of the coupling, and thus allowing the band to be drawn through and turned back over the burr.

It will be seen, therefore, that, while in a bale-tie both ends of the strap are turned under and moused by the expansion of the compressed material in this band, there is no opportunity to turn in the free end for the purpose of mousing it, and reliance must be had upon the tensile strength of the metal and its stiffness at the point where it turns over the burr. An apparatus for this purpose is illustrated in Fig. 6 of the drawings, and in Fig. 7, which is a cross-section in line x x of Fig. 1, showing the manner in which a chain-compressor operates to fit the band to its place.

20 F is a yoke, having attached to it at one end a flexible chain or strap, G, which chain G is provided with abutments, in this case consisting of the flexible rolls h of an ordinary lathe-chain. At the other end of this yoke F is pivoted a nut, I, through which works the hand-screw K, carrying on its end a swiveled jaw, L, to take hold of the abutments referred to in the flexible strap.

25 The way this mechanism works to apply one of the bands referred to is as follows: The hose being slipped upon the coupling, a burr having a strap attached to it is put round in its proper place and the free end of the strap passed through the burr upward. This 30 apparatus is taken and the flexible band G put round the hose, and the abutment h is engaged with the jaw K. The burr should be adjusted so as to come at the place of the yoke, the end of the yoke to which the chain is fastened being placed over the edges of the burr. Upon 35 tightening the screw it will be seen that the burr is itself drawn down upon the hose. The band D is then compressed by the chain, or its equivalent, into and upon the hose throughout the entire circumference of the hose, and 40 will thus be shortened by the traverse of the chain over it, and will be forced up at its free end through the burr. When a sufficient amount has been protruded through the burr 45 the free end is turned down and clinched by hammer or otherwise, and, the screw being loosened, it will be found that the hose is tightly banded to the coupling. By this apparatus referred to a sufficient strain can be 50 brought to bear upon the exterior of the hose in the place of the band to crush the neck of the coupling itself, and consequently it is very

55 evident that it is easy, with this simple tool, to repair, with these bands, a large piece of hose which may happen to burst, on occasion 60 of a fire, in the street, simply by cutting off the broken part of the hose and reinserting the coupling or a short piece of tube.

65 This method, too, offers great advantages for the coupling together of inflexible pipes by means of flexible wrappings or tubes connecting their ends, which is a desirable thing in hydraulic mining. So, also, these bands may be readily applied by described apparatus to any compressible covering for a non-compressible core.

70 I have described a tool herein for applying the band to the hose in a peculiar manner, and in an application for Letters Patent now pending I have separately claimed the same. 75 I do not intend to confine myself, however, to this particular mechanism for applying the band; yet I prefer one that shall operate in principle to compress the band upon the hose as herein set forth, although other means may 80 be employed.

75 It will be seen that this tool differs materially from the tools described in my former patent, and is applicable to bands which have no projections for the engagement of the jaws 85 in order to draw the band tightly upon the hose, and that by the aid of this tool a much greater range of sizes can be applied with one instrument, and also that the compression of the band upon the hose and with its substance 90 is much more uniform, and does not depend at all upon the stretch of the material of the band, nor is it interfered with by the application of the band upon the surface of the hose.

95 I therefore claim as my invention—

1. The combination, with a non-compressible core surrounded by a compressible casing, of a burr, C, in combination with a flexible metallic band, D, compressed and drawn upon the exterior of the compressible envelope by means exterior to itself, substantially as described.

2. In combination with a compressible body, the burr C and band D, surrounding the same and tightly drawn upon and compressed into the same by a positively-actuated flexible band applied over the said band D and tightly drawn upon it, whereby said band D is shortened to its holding position, substantially as described.

OSCAR T. EARLE.
